UNITED STATES PATENT OFFICE

RALPH F. SENESE, OF BROOKLYN, NEW YORK

DESIGN FOR A TOILET-ACCESSORY CONTAINER

Application filed July 26, 1929. Serial No. 32,214. Term of patent 7 years.

To all whom it may concern:

Be it known that I, RALPH F. SENESE, a citizen of the United States, residing at Brooklyn, county of Kings, city of New York, and State of New York, have invented a new, original, and ornamental Design for Toilet-Accessory Containers, of which the following is a specification, reference being had to the accompanying drawing, forming a part thereof.

I claim:

The ornamental design for a toilet accessory container, as shown.

RALPH F. SENESE.
